UNITED STATES PATENT OFFICE.

JULIUS DON NORTHRUP, OF GIDDINGS, TEXAS.

RIDING-SADDLE.

SPECIFICATION forming part of Letters Patent No. 443,241, dated December 23, 1890.

Application filed June 28, 1890. Serial No. 357,029. (No model.)

To all whom it may concern:

Be it known that I, JULIUS DON NORTHRUP, a citizen of the United States, residing at Giddings, in the county of Lee and State of Texas, 5 have invented certain new and useful Improvements in Riding-Saddles; and I do hereby declare that the following is a full, clear, and exact description of the invention, which will enable others skilled in the art to which 10 it appertains to make and use the same.

This invention relates to riding-saddles; and it has for its object to provide an improved saddle of this class of more durable and comfortable construction than those now 15 generally used, and one which is designed to remedy certain other defects hereinafter mentioned.

With these objects in view my invention consists in the peculiar construction and arrangement of the various parts, such as shown 20 in the drawings, and more fully set forth hereinafter.

In the drawings, Figure 1 is a perspective view illustrating my improved saddle in 25 course of construction. Fig. 2 is a similar view illustrating the same at a more advanced stage. Fig. 3 is a similar view of the completed saddle. Fig. 4 is a bottom or inverted plan view. Fig. 5 is a sectional view 30 on the line xx , Fig. 2.

Corresponding parts in the drawings are denoted by the same letters of reference.

Referring to the drawings, A designates the tree, which may be in the main of the usual 35 or any preferred pattern, and provided with a central longitudinal opening a , forming side bars $a' a'$.

B B designate the stirrup-straps, which are passed around their adjacent side bars, 40 in lieu of across the latter, as is generally the case. Covering the opening a between the side bars is a piece of leather C, of approximately H shape and disposed transversely across the tree, said piece extending from 45 near the point of the cantle to the fork of the tree. The recesses $c c$ formed in the leather C are located coincident to the stirrup-straps and of a corresponding breadth, whereby the piece C is adapted to fit down upon the tree 50 at either side of the straps, and the edges of the piece C adjacent to the straps being of the same thickness as the latter a smooth un-

broken surface is thus secured. The front and rear edges of the leather C are also trimmed or beveled, so as to obviate the formation of shoulders at these points, and thus make the smooth unbroken surface continuous. After the leather piece C has been secured to the tree a strainer D may then be secured over the same. If desired, however, 55 and it is generally found preferable, a thin piece of leather S may be employed to cover the piece B; but this is not essential. The strainer D is formed of sheet metal or other non-yielding material and of approximately 60 T shape, thus comprising a rearwardly-projecting longitudinal wing d and oppositely-projecting transverse wings $d' d'$ at the front end of the strainer. The strainer extends from the cantle to the fork, the wing d covering 65 the rear portion of the opening a in the tree and the wings d' covering the stirrup-straps and projecting at the sides thereof over the leather piece C. It will thus be apparent 70 that by the employment of this non-yielding strainer any depression at the opening a is obviated, which so often occurs with other forms of saddles, resulting in rubbing of the horse's back, besides producing an uncomfortable seat. If padding or filling is desired 75 on this strainer, it may be secured; but ordinarily this will not be necessary, and a covering E is placed over the strainer and tacked down, said covering extending sufficiently in all directions, as shown, to cover all 80 the aforementioned parts.

The practicability and advantages of my invention will be readily understood by those skilled in the art to which it appertains. From the above it will be seen that a cheap, 90 simple, comfortable, and durable saddle is formed, one in which all longitudinal depression is effectually prevented and in which the surface of the seat is unbroken by the stirrup-straps. It will further be obvious 95 that while the leather piece C is herein shown with all its parts integral, it is not essential, as the same may be formed in two sections, a forward and rear strip, as shown in dotted lines, Fig. 1.

I claim as my invention—

1. In a riding-saddle, the combination, with a tree, of the stirrup-straps passed around the bars thereof, a filling arranged at each

side of the straps and of a corresponding thickness to the latter at the opposing edges, and a non-yielding strainer covering the opening in the tree and the upper portions of the straps, substantially as and for the purpose set forth.

2. In a riding-saddle, the combination, with a tree, of the stirrup-straps passed separately around the bars of the same, the filling-piece 10 of approximately H shape, having its recesses corresponding to and adapted to receive the coincident portions of the stirrup-straps, the edges of said filling-piece adjacent to the latter being of the same thickness, and the non-yielding strainer extending over the filling-piece and the stirrup-straps, substantially as 15 and for the purpose set forth.

3. In a riding-saddle, the combination, with

a tree, of the stirrup-straps passed separately around the bars of the same, and the approximately H-shaped filling-piece having its recesses adapted to receive the adjacent portions of the stirrup-straps and its contiguous edges of corresponding thickness with the latter, the front and rear edges of said filling-piece being beveled, whereby a smooth and unbroken top surface is formed throughout the length of the tree, substantially as set forth. 20 25

In testimony whereof I affix my signature in presence of two witnesses.

JULIUS DON NORTHUP.
